UNITED STATES PATENT OFFICE.

CHARLES P. HOWARD AND FRANK E. HOWARD, OF HARTFORD,
CONNECTICUT.

FOLDING BARRIER AND DOOR-HOLDER.

SPECIFICATION forming part of Letters Patent No. 743,079, dated November 3, 1903.

Application filed May 28, 1903. Serial No. 159,138. (No model.)

To all whom it may concern:

Be it known that we, CHARLES P. HOWARD and FRANK E. HOWARD, citizens of the United States, and residents of Hartford, in the county of Hartford and State of Connecticut, have invented certain new and useful Improvements in Folding Barriers and Door-Holders, of which the following is a full, clear, and exact specification.

- 10 This invention is an improved folding barrier and door-holder, which may be located across an open doorway or folded entirely out of the way at the side of the doorway and safely latched in its folded position. It is herein shown as applied to the sliding doorway of a railway-car, serving not only as a barrier to protect passengers and others from falling out, but also serving as a means for holding a sliding door in an open position.
- 15 Figure 1 of the drawings is a side view showing this embodiment of the invention in operative position across a doorway serving as a safety-barrier and also to hold the sliding door thereof in a predetermined position.
- 20 Fig. 2 is a plan view in section, taken on the line 2 2 of Fig. 1. Fig. 3 is an end view in section, taken on the line 3 3 of Fig. 1. Fig. 4 is a side view similar to Fig. 1, but showing the barrier in its folded position at one side 25 of the doorway and with the sliding door in its closed position. Fig. 5 is a plan view in section, taken on the line 5 5 of Fig. 4. Fig. 6 is a plan view, in reduced scale, of the vestibule of a special form of electric car with 30 this invention applied thereto.
- 35 The bar 21 is pivotally attached to the hinge-block 22, which slides in the journal 24 of the slideway 23. The latter is secured to the frame 25 at the side of the doorway, and 40 when the device is used in connection with a sliding door, as is herein shown, the slideway 23 may form one side of the groove into which the leading side of the door extends when closed. The form of the slideway may 45 be suited in many ways to the moldings or trimmings of the car or other structure to which it is applied. It is here shown as being set in between the sections 28 of the moldings which form one side of the groove 29 50 for the door. The exterior contour of the slideway 23, its cap 26, and the socket 27 may

be adapted in contour to the contour of that molding, the parts being preferably secured by means of screws 19. The opposite end of the bar 21 is provided with a knob 30, which 55 in the position shown in Fig. 1 serves to support that end of the bar and also to hold the sliding door 21 in a partly-open position by engaging with a catch device consisting of the slotted latch-plate 32, which is secured to 60 the front edge of the sliding door 31 and having a recess 33, in which the knob rests.

The opening into the recess 33 is wide enough at its upper end to admit the head of the knob 30, but is narrowed down at its 65 lower end to substantially the width of the neck of the knob 30, thus making the recess T-shaped at its lower end, so that the bar is held securely in the position shown, from which it can only be removed by raising it to 70 the position shown by the dotted lines at A, the curved or inclined inner wall 34 of the recess 33 facilitating the withdrawal of the bar by the operation. The free fit of the sliding block 22 in the slideway 24 permits what 75 little side motion is necessary to latch and unlatch the bar. The bar 21 thus serves to effectively guard the opening between the door 31 and the frame 25 when for ventilation or other purpose it is desired to secure 80 the door in its half-open position, as shown. The plate 32 is also provided along its front edge with a recess 35, so shaped as to serve as a convenient hold for the hand when withdrawing the door from its recess 36 in the car- 85 frame, Fig. 6.

When it is desired to close the door 31 or to slide it back for the full width of the opening, the bar 21 is raised out of the recess 33 and swung on its pivot in the block 22 toward 90 the frame 25 and its end dropped into the socket 27, fitted to receive it, and secured to the frame 25, the block 22 meanwhile sliding upward as far as necessary in the slideway 23. The socket is recessed to receive the end 95 of the bar and its knob, the neck of the latter resting in the seat 37, which holds it against lateral movement. The door 31 can now be drawn to the position shown in Figs. 4 and 5, so as to close the entrance, or it can 100 be slid back, so as to open the passage to its fullest width. When the door is thus opened

and the barrier folded, the doorway is left wide open for the exit or entrance of the passengers without any projecting parts to catch their clothing or their persons in case of a 5 crowd.

In the car-vestibule shown in Fig. 6 the line 50 represents the longitudinal center line of the car, that half of the vestibule which is partly cut away being similar in shape and 10 arrangement to the other half. The sliding door 47 leads to the interior of the car. The swinging door 41 is hinged at 42 and when in the position D serves to close the passage-way leading off the end of the car. In the 15 position C it serves to inclose the motorman and to prevent the use of the passage-way on that side of the car.

In the position B it serves to inclose the controller 45, the brake-valve 46, and other 20 apparatus placed near them, so that they shall not in any way interfere or be interfered with during the exit and entrance of the passengers. When in this position, B, the door also engages the angle-piece 40, provided 25 on the bar 41, thus effectually securing the bar 21 in its folded position, and thereby guarding it from meddlesome or accidental displacement from its seat in the socket 27.

These devices may be applied to any doorway 30 independently of the door thereof by attaching the slideway at one side of the door-frame, as herein shown, and by attaching the catch device 22 to the opposite door-frame. When applied to a sliding door, as here shown, 35 the devices may be turned end for end, attaching the slideway 23 to the door and a catch-plate 32 to the frame of the doorway. In many other ways which will suggest themselves to those skilled in the art these devices 40 may be modified in form and manner of application to suit varying environments or conditions of service.

We claim as our invention—

1. A folding barrier for doorways, comprising 45 a hinged bar provided with latching means, a slideway for the hinged portion of the bar, and a catch device coöperating with the latch of the bar.

2. A folding barrier for doorways, comprising 50 a bar, a hinge-block therefor, a slideway for the hinge-block, and a latch device for the bar.

3. A folding barrier for doorways, comprising

ing a bar, a hinge-block pivoted thereto, a slideway for the hinge-block, latching devices 55 for holding the bar in operative position across the doorway, and latch devices for holding the bar in folded position at one side of the doorway.

4. A folding barrier for doorways, comprising 60 a bar provided with a hinge, a slideway for the hinged portion of the bar, means for attaching the slideway at one side of the doorway, means for latching the bar in operative position across the doorway, and means for 65 latching the bar in its folded position at one side of the doorway.

5. A folding barrier for doorways, comprising 70 a hinged bar, a slideway therefor, means for attaching the slideway at one side of the doorway, a knob appurtenant to the bar, and a slotted latch-plate for attachment to the opposite side of the doorway.

6. A folding barrier for doorways, comprising 75 a hinged bar, a slideway therefor for attachment at one side of the doorway, a knob appurtenant to the bar, a slotted latch-plate for receiving the knob to latch the bar in its operative position across the doorway, and means for attaching the latch-plate to the 80 door.

7. The combination with a doorway, of a sliding door therefor, a swinging door adjacent to the doorway, and a folding barrier for the doorway comprising a hinged bar, a 85 slideway therefor, latching devices for latching the door in operative position across the doorway, and in its folded position at one side of the doorway, and means appurtenant to the bar for engaging behind the swinging 90 door to retain the bar in its folded position.

8. The combination with a barrier having a knob, of a latch-plate having a substantially T-shaped recess for retaining the knob, the 95 said recess opening laterally at its entering end to permit the lateral insertion and withdrawal of the knob, and provided with an inner inclined wall for guiding the knob laterally into and out of the T-shaped recess.

Signed at Hartford, Connecticut, in the 100 presence of two subscribing witnesses.
